UNITED STATES PATENT OFFICE

2,374,938

FLOATING CARRIER FORTRESS

James Hundley, Columbus, Ohio

Application April 6, 1944, Serial No. 529,799

1 Claim.

(Cl. 114—4).

This invention relates to a floating carrier fortress, one of the objects being to provide a structure which, by reason of its new and novel construction, will not only float under a heavy load, but can also be made in such proportions as to embody therein all of the essentials of a large task force, thereby permitting a complete unit, including men, airplanes, mechanized ground vehicles, and artillery of all types, to be transported over a body of water and permit a mass assault on a selected objective.

A further object is to provide a carrier fortress including a deck, which can be armored, and a ramp leading downwardly from the deck whereby airplanes as well as mechanized land equipment, can travel between the deck and hangars or storage spaces of ample size beneath the deck.

A still further object is to provide a carrier fortress in which are formed a number of slips adapted to receive one or more fighting ships or the like forming a part of the task force and which can be utilized for propelling the carrier fortress toward its objective.

A still further object is to construct a carrier fortress that will afford maximum protection for the propelling ships so as to minimize or altogether eliminate danger from torpedoes.

Another object is to construct the carrier fortress of superposed layers of timbers built up to a predetermined size so that the resultant structure will float with a large portion thereof below water level but sufficiently tight to permit the use of deep recesses in the body of the structure which can be used for any needed purposes such as the storage of motorized equipment, the housing of personnel, etc.

Another object is to provide the structure with any suitable means for holding together the timbers forming the various layers so that relative displacement will be prevented, the interstices being sealed by any suitable plastic or other filler meeting the requirements.

Another object is to provide a carrier fortress the deck of which can constitute an area on which airplanes can land and from which they can take off.

Another object is to provide the carrier fortress with protective armor at properly located points so as to minimize injury by torpedoes.

A still further object is to provide the carrier fortress with gun-emplacements so that artillery of heavy caliber and also anti-aircraft guns, and the like, can be disposed wherever found desirable both for defensive and offensive purposes.

A still further object is to utilize timbers which can be assembled end-to-end in sections, these timbers being permanently joined and, if desired, being hollow to increase their buoyancy.

With the foregoing and other objects in view

which will appear as the description proceeds, the invention consists of certain novel details of construction and combinations of parts herein-after more fully described and pointed out in the 5 claim, it being understood that changes may be made in the construction and arrangement of parts without departing from the spirit of the invention as claimed.

In the accompanying drawings the preferred 10 form of the invention has been shown.

In said drawings

Figure 1 is a top plan view of the complete carrier fortress, some propelling ships being shown assembled therewith.

15 Figure 2 is an enlarged section through a portion of the back end of the carrier fortress, said section being taken on the line 2—2, Figure 1.

Figure 3 is an enlarged vertical transverse section through a portion of the carrier fortress, 20 said section being taken on the line 3—3, Figure 1.

Figure 4 is an enlarged vertical section through a portion of the fortress and illustrating the arrangement of the timbers or logs forming the body of the carrier fortress, parts being broken 25 away.

The main or body portion of the structure constituting this invention is made up of superposed 30 layers of logs or timbers and each layer can be of any desired predetermined area. The logs of each layer are arranged close together and parallel and are also positioned so as to extend across or transversely of the logs constituting the next adjoining layers. Each layer will extend throughout the extent of the width and length of the 35 craft and as before stated, this area can be such as to accommodate a great number of men and large quantities of equipment so that, if desired, a complete battle unit of large proportions can be carried thereby. It is of course necessary to place logs in each layer not only in parallel relation but also end-to-end, but wherever it is desired to provide within the structure necessary 40 spaces for the storage of men and equipment, the logs can be eliminated to any depth required.

45 In the drawings superposed layers of logs have been indicated at A and B, the logs A being extended across and contacting with the logs B. Enough layers of logs are provided to insure a structure of the proper height or depth and a sufficient number of logs are provided in each 50 layer to insure a structure of the desired area. It is preferred to form spaces between the corner portions of adjoining logs as shown at 1 and these spaces can be filled with a suitable sealing

55 plastic 2 or the like so that when all of the layers of logs are assembled, a solid mass is provided which will not become distorted. Furthermore the logs of the different layers are all joined together by any suitable tie devices such as cables 60 3 looped therearound at intervals.

While the logs or timbers can be solid, it generally will be found advisable to form all of the logs, except those at the exposed sides or ends of the structure, with longitudinal bores 4 and, if preferred, each of these bores can be provided with a lining 5 of metal. As no one timber would extend the full length of the carrier fortress or the full width thereof, some means must of necessity be provided for holding logs end-to-end. One such means has been shown in Figure 4 wherein a counterbore 6 is formed in one end of one log or timber for the reception of the reduced end 7 of the next adjoining timber. Both the reduced end 7 and the wall of the counterbore 6 are provided with annular grooves 8 and the grooves in the two logs or timbers are adapted to match or register when the timbers are brought together end to end. All of the grooves can communicate through a longitudinal groove or channel 9 from which is extended an opening 10. Thus following the assembly of two or more logs or timbers end to end as described, a suitable plastic material 11 can be caused to flow through the opening 10 to the channel or groove 9 and thence to the various matching annular grooves 8 where the said material will set and form keys serving to hold the abutting timbers against displacement relative to each other. As shown in Fig. 4 the tubular lining 5 can be closed at its ends and can bridge and seal the joint between the abutting members.

Obviously each layer can be formed as a complete unit after which another layer of timbers or logs placed at right angles to those of the other layers, can be assembled. This procedure can be followed until the structure has been built up to its predetermined height and during this assembly of the parts, tie devices 3, as before explained, can be tightened about the timbers of two or more layers so as to hold them firmly together. Furthermore during this operation of building up the body of the structure, the spaces between the timbers or logs can be filled with a suitable plastic as indicated at 2.

As before explained, during the construction of assembly of the plurality of layers of timbers, spaces can be left wherever desired and as indicated, for example, at C, D and E. These can be of any desired size, shape and number and can be utilized for any purposes deemed suitable. In addition thereto, slips are provided in the back portion of the carrier fortress as indicated at F, these slips being parallel and each being of a size sufficient to receive a ship forming a part of a task force. This will be apparent by referring to Fig. 1 wherein ships have been indicated at S. Obviously the structure of timbers in front of and at the sides of these slips will afford excellent protection against damage by torpedoes and the bottoms of the slips can be closed as shown in Fig. 2 to afford protection from undersea explosions, as from mines. Supplemental protection can be afforded by extending a framework 12 rearwardly from the carrier fortress so that a guard 13 in the form of netting of any desired construction can be supported back of and across the open ends of the slips, these extending downwardly under the water level a sufficient distance to prevent torpedoes from entering the slips.

Gun-emplacements 14 can be located adjacent

to the sides of the carrier fortress near the top thereof and on these artillery pieces of various kinds can be mounted as indicated for example at 15 and 16. These can be of large caliber or 5 small caliber and can be used for either offensive or defensive purposes.

The entire top of the carrier fortress is protected preferably by armor plate, indicated at 17 and leading from this armored top or deck, is a ramp 18 along which planes and mechanized land equipment can move in travelling between the deck and the housing space E thereunder. Obviously airplanes can land on or take off from the deck G formed by the armor plate 17.

Protective armor can be extended around the carrier fortress as indicated at 19 to a suitable depth below the water level and at any suitable distance inwardly from this outer protective armor, other protective armor 20 can be extended downwardly. Thus should any of the outer side or end portions of the carrier fortress become damaged by projectiles or the like, the inner armor 20 will serve as an added protection for the fortress.

As before pointed out, there is no limitation as to the size of the carrier fortress to be made in accordance with the present invention. It is preferred that the same be of such size as to carry a complete battle unit including personnel, mechanized land equipment, airplanes, and escort vessels. These escort vessels can be either battleships or war-craft of other types and are secured within the slips F, and serve not only as the means for propelling the carrier fortress to its destination but also provide a force always at hand prepared to leave the slips and engage in battle with any attacking force. Obviously the guard 13 can be so mounted as to be removed so as not to interfere with the entry or emergence 35 of the ships relative to the slips.

It is to be understood that the metal tubular linings for the logs are designed to increase the buoyancy of the structure by preventing gradual seepage of water into the center of the logs or timbers.

The terms "logs" and "timbers" are used synonymously, it being obvious that untrimmed logs might be used in the construction of the device or said logs might be dressed to form preshaped heavy timbers.

The tubes located within the logs permit air to be held in the submerged logs under pressure, thereby to resist seepage of water into the logs and also aid the hollow logs in resisting crushing when submerged at considerable depths and subjected to excessive water pressure.

What is claimed is:

A carrier fortress including superposed layers of hollow timbers, the timbers of each layer being connected end to end in parallel rows and extended across the timbers of the next adjoining layers, a sealed tubular metal lining in each hollow log, means for tying the timbers together, there being interstices between portions of the timbers, and a filler in the interstices, there being spaces between some of the timbers providing service areas, and a ramp leading from the top of said structure to one of said areas for the passage of airplanes and land equipment to and from said area.

JAMES HUNDLEY.
